Primary Examiner — John Windmuller*Assistant Examiner* — John R Yeh(74) *Attorney, Agent, or Firm* — Coastal Patent Law Group, P.C.(57) **CLAIM**

The ornamental design for a GPS antenna assembly, as shown and described.

DESCRIPTION

FIG. 1 shows a front side of a GPS antenna assembly embodying the new design;

FIG. 2 shows a bottom side thereof;

FIG. 3 shows a rear side thereof; and,

FIG. 4 shows a left side thereof.

All claimed surfaces of the design are flat and coplanar.

1 Claim, 2 Drawing Sheets(56)
